United States Patent Office

Des. 201,906
Patented Aug. 10, 1965

201,906

SPOON

Luigi Di Benedetto, 704 Centinela Ave., Inglewood, Calif.

Filed Nov. 27, 1964, Ser. No. 82,821

Term of patent 14 years

(Cl. D44—29)

FIGURE 1 is a perspective view of a spoon embodying my new design;

FIGURE 2 is an elevational view on an enlarged scale of the spoon shown in FIGURE 1;

FIGURE 3 is a plan view on an enlarged scale of the spoon shown in FIGURE 1;

FIGURE 4 is a transverse cross-section view taken along line 4—4 of FIGURE 3 on an enlarged scale; and

FIGURE 5 is an end view on an enlarged scale of the spoon shown in FIGURE 1.

I claim:

The ornamental design for a spoon, substantially as shown.
